UNITED STATES PATENT OFFICE.

LEVI J. WING, OF BROOKLYN, NEW YORK.

ABDOMINAL PROTECTOR.

SPECIFICATION forming part of Letters Patent No. 351,893, dated November 2, 1886.

Application filed January 20, 1886. Serial No. 189,133. (No model.)

To all whom it may concern:

Be it known that I, LEVI J. WING, of Brooklyn, in the county of Kings and State of New York, have invented certain new and useful 5 Improvements in Abdominal Protectors, of which the following is a specification.

This invention relates to an improved abdominal protector by which the abdomen and spine are kept warm and comfortable, to be 10 used by males, females, and children; and the invention consists of an abdominal protector formed of two pieces of flannel or other suitable material, said pieces overlapping each other at the front part and being connected 15 by fastening devices of the front parts, re-enforced by an extra layer of fabric at the back, and adjusted by lacings at the sides, as will be more fully described hereinafter, and finally pointed out in the claim.

20 In the accompanying drawings, Figure 1 represents a perspective view of my improved abdominal protector, shown as applied to the body. Figs. 2 and 3 are respectively a front view and a rear view of the same, drawn on a larger scale; and Fig. 4 is a horizontal section on line $x x$, Fig. 3.

Similar letters of reference indicate corresponding parts.

Referring to the drawings, A represents my 30 improved abdominal protector, which is made of two sections, $a a$, of flannel, chamois-skin, or other suitable material, which sections are stitched together at the back and overlapped at the front part, and connected at the overlapping parts by buttons or other fastening devices $b b$. The front parts of the sections a overlap each other to such an extent that the abdomen is well covered by two layers of fabric.

The rear part of the protector A is made of 40 two layers of fabric by stitching a tapering layer, d , of flannel or other fabric over the rear parts of the sections $a a$, the extra layer, d , serving to keep the lower part or small of the back warm and comfortable. 45

The protector is provided at its upper part, near the hips, with slits or gores, which are connected by lacing-strings, buttons, or other fastening devices, $e e$, as shown in Fig. 2.

By lacing strings $e e$ the protector can be 50 snugly adjusted to the waist without undue pressure on the same, so as to fit easily around hips and abdomen.

The protector may be medicated with suitable substances, and is intended to keep the 55 lower part of the back and the abdomen well protected against cold, so as to impart a comfortable feeling of warmth to the lower part of the body.

Having thus described my invention, I 60 claim as new and desire to secure by Letters Patent—

An abdominal protector made of two sections, united at the back by a back seam and provided with overlapping portions at the 65 front, means for connecting the said overlapping front portions and lacings at the upper parts of the sides, and an extra layer of fabric, wider at the upper end and narrower at the lower end, stitched to the back part across the 70 back seam, substantially as set forth.

In testimony that I claim the foregoing as my invention I have signed my name in presence of two subscribing witnesses.

LEVI J. WING.
